COVERED DISH OR SIMILAR ARTICLE

Norman L. Chapman, Lincolnwood, Ill., assignor to National Portion Control, Inc., Chicago, Ill.

Filed Sept. 7, 1971, Ser. No. 178,530

Term of patent 14 years

Int. Cl. D7—01
U.S. Cl. D44—15 A

FIG. 1 is a front elevational view of a covered dish or similar article showing my new design;

FIG. 2 is a front elevational view similar to that of FIG. 1, but with the dish rotated through an angle of 45 degrees;

FIG. 3 is a top plan view thereof; and

FIG. 4 is a bottom plan view thereof.

I claim:

The ornamental design for a covered dish or similar article, as shown.
